UNITED STATES PATENT OFFICE

2,102,473

METHOD OF MAKING RETAINER LOCKS

Eugene A. McBride, Cleveland, Ohio, assignor
to Thompson Products, Incorporated, Cleve-
land, Ohio, a corporation of Ohio

Application October 8, 1936, Serial No. 104,619

2 Claims. (Cl. 153—2)

This invention relates to a method of making retainer locks, such as the split, tapered collars or bushings used in valve assemblies to secure the spring retainer plates in position.

5 In accordance with this invention, a metal strip or bar having substantially the desired cross section of the finished retainer lock is subjected to a series of severing and forming operations to produce a lock of the desired finished dimensions. 10 The metal strip is advanced into position between male and female forming dies, where it is temporarily supported upon stripping members or kick-out bars. Upon relative movement of the dies toward each other, a blank is severed from 15 the end portion of the strip of a length slightly greater than the finished length of the retainer lock, and this blank is bent into substantially semi-cylindrical form through the further action of the dies. While the blank is still supported between the forming dies, knives are moved in 20 radially of the formed blank to sever the edges thereof to the proper finished length of the collar or retainer lock member.

By employing the forming dies as the supporting medium for the formed blank during the final severing or trimming operation, the use of an auxiliary holding member is eliminated and the operation thus simplified. This novel feature of 30 my invention also tends toward greater precision in the manufacture of the retainer locks to the desired dimensions.

It is therefore an important object of this invention to provide a method of forming valve spring retainer locks and similar devices, wherein a continuous metal strip is first severed and the severed portion bent into the desired form but of a length greater than that of the finished retainer lock, and the formed blank trimmed to the final dimensions while supported between the forming surfaces themselves.

40 Other and further important objects of this invention will be apparent from the disclosures in the specification and the accompanying drawings.

This invention (in a preferred form) is illustrated in the drawings and hereinafter more fully described.

On the drawings:

Figure 1 is a fragmentary elevational view, partly in section, of the die forming elements used in carrying out the method of this invention.

50 Figure 2 is a fragmentary sectional view taken substantially along the line II—II of Fig. 1, with parts in elevation.

Figure 3 is a fragmentary plan view of a metal

strip from which the valve spring retainer locks are formed.

Figure 4 is an end plan view of a finished valve spring retainer lock member.

Figure 5 is an elevational view of the finished 5 lock member of Fig. 4.

Figures 6 to 9 inclusive illustrate various steps in the making of the valve spring retainer locks, showing the upper or female forming die in elevation and the lower, or male forming die and associated parts in section.

As shown on the drawings:

The reference numeral 10 indicates the bed plate of a suitable type of forming machine for carrying out the method of this invention. A die 15 11 is mounted in said bed plate for vertically reciprocating movement and carries at its upper end a male forming member 12 having a convex forming surface 13. Stripping members, or kick-out bars 14 and 15 extend through the lower portion 20 of the die 11 to project on each side of the male die head 12. Knives 16 and 17 are positioned in horizontal, opposed relation for movement radial- 25 ly of the cylindrical forming surface 13 of said male die 12.

An upper die 18 is carried by a suitable holding member 19 for vertical movement in alignment with the lower die 11. Said upper die 18 is provided with a tapered concave forming surface 20 adapted to cooperate with the forming surface 30 13 of the lower die.

In accordance with my method, the valve spring retainer locks are formed from a continuous strip 21 (Fig. 3) of metal which has preferably been 35 rolled or otherwise worked to provide one or more beads 22 along one broad face of the strip. Said strip 21 is also preferably tapered in cross section to provide a section similar to that of the finished retainer lock.

As shown in Figs. 1 and 2, the strip 21 is ad- 40 vanced through a slot 23 of conforming cross section provided in the bed plate 10, so that an end portion of said strip 21 is guided and supported upon the ends of the kick-out bars 14 and 15 above the male die 12. Said kick-out bars 14 and 45 15 are provided at their ends with grooves 24 for receiving the bead 22, thus insuring proper alignment of said bead 22 with the groove 25 formed in the surface 13 of the male die 12.

As the upper die 18 is lowered, it first severs 50 the end portion of the strip 21 to provide a blank 27 which is of greater circumferential length than the length of the finished retainer lock, or collar. As the upper die 18 moves the blank 27 against the forming surface 13 of the male die 55

12, the kick-out bars 14 and 15 are lowered clear of the work. At the same time the blank 27 is bent into substantially semi-cylindrical form between the forming surfaces 13 and 20 of the lower 5 and upper dies, respectively.

After the forming of the blank 27, and while the blank 27 is still held between the cooperating dies 12 and 18, the knives 16 and 17 are operated to move relatively toward each other radially of the semi-cylindrical blank to trim the longitudinal edges 28 and 29 thereof. To insure accuracy in this severing operation, the head 12 of the lower die is provided with sharp under shoulders 30 with which the cutting edges of said 15 knives 16 and 17 cooperate.

After the severing operation has been completed, the upper die 18 is raised clear of the bed plate and the kick-out bars 14 and 15 are elevated to strip the finished retainer lock member, indicated by the reference numeral 31 (Fig. 9), from the lower die 12. Suitable means (not shown) 20 may be employed for removing the finished retainer lock member from the kick-out bars 14 and 15.

The operation is then repeated to form identical valve spring retainer lock members, or half collars, which are used in pairs in the usual manner for holding the valve spring retainer plate in place in valve assembly. For such purpose, it is 30 extremely necessary that the lock members be accurately dimensioned and this is one of the advantages of the method just described.

An important feature of my method which contributes to the precision as to the dimensions of the final lock member, is the provision for the supporting of the blank between the forming surfaces of the upper and lower dies during the final trimming operation. The formed blank has 35

no opportunity to spring out of shape, owing to the fact that it is firmly held under considerable pressure between the faces of the dies. Consequently, the relatively heavy impact of the knives 16 and 17 in the trimming operation cannot alter 5 the shape of the formed blank. The excess metal along the longitudinal edges of the formed blank can also be very accurately trimmed off to leave finished surfaces that need no further machining.

I am aware that many changes may be made 10 and numerous details of construction may be varied through a wide range without departing from the principles of this invention, and I, therefore, do not purpose limiting the patent granted hereon otherwise than necessitated by 15 the prior art.

I claim as my invention:

1. In the method of making valve spring retainer locks from a metal strip, the steps which comprise severing a blank from said strip of a 20 length slightly greater than the length of a finished lock, forming said blank to the shape of a finished lock between forming dies and severing opposite edges of said blank while supported between said dies to produce a lock of the desired 25 finished dimensions.

2. The method of making collars from metal strip, which comprises guiding and supporting an end of said strip upon stripping members between male and female dies, severing a blank from 30 said strip end of greater length than that of the finished collar, bending said blank to the desired shape between said dies, severing the edges of said shaped blank while held between said dies to produce a collar of finished dimensions and stripping said collar from said dies by means of said 35 stripping members.

EUGENE A. McBRIDE.
